DISPLAY APPARATUS

Charles J. Henderson, Yazoo City, Miss.

Application September 20, 1938, Serial No. 230,864

2 Claims. (Cl. 46—55)

This invention appertains to new and useful improvements in display apparatus and more particularly to a display apparatus which is wind-driven and which involves characters or figures activated by the motion of the impeller.

The principal object of the present invention is to provide an animated display apparatus which is wind-driven and which in operation will be highly attractive and which can be used to advertise or attract attention in front of restaurants and other business places.

These and other objects of the invention will become apparent to the reader of the following specification.

15 In the drawings:

Figure 1 is a side elevational view.

Figure 2 is a front elevational view.

Figure 3 is a horizontal sectional view.

20 Figure 4 is a fragmentary transverse sectional view taken substantially on the line 4—4 of Figure 3.

Figure 5 is a perspective view of the trip mechanism.

25 Figure 6 is a sectional view taken substantially on the line 6—6 of Figure 3.

Figure 7 is a sectional view taken substantially on the line 7—7 of Figure 2.

30 Referring to the drawings wherein like numerals designate like parts, it can be seen that numeral 5 denotes a post upon which the body is rotatably mounted as at 7.

35 On the body 6 is the cylindrical shell 8 having the headers 9 and 10. The crankshaft 11 extends through these headers and shell 8 and has the cranks 12 and 13.

At the outer end of the shaft 11 is the wind-wheel generally referred to by numeral 14 and this consists of the hub 15 having spokes 16 connected to the annulus 17 and from the annulus 40 17 extend the vanes 18. These vanes are connected by having the annulus rod or wire member 19 disposed through the trailing edges thereof and retainer members 20 each having an eye 21 at each end thereof are provided to hold the 45 vanes against shifting on the wire annulus 19 as suggested in Figure 7.

In carrying out the present invention, there are a pair of figures 22—23 simulating wood sawers and a third character 24 simulating a 50 wedge driver.

Extending laterally from the body 6 are the step boards 25—25 for the figures 22, 23 and 24. The figures 22 and 23 are each constructed by having the leg members 26 thereof fixed to the 55 corresponding step board 25 while the body por-

tion 27 thereof is pivotally secured as at 28 to the legs 26. The arms 29 and 30 are in turn pivotally secured as at 31 to the body 27 and the end portions of these arms 29 and 30 are apertured to receive the upstanding pintles 32 or handle portion of the elongated bar or saw-simulating element 33 which is provided with an enlarged intermediate portion 34. This enlarged head portion 34 is provided with the slot 35 therein for receiving the crank 12 of the crankshaft 11. 10 Obviously as the wind-wheel 14 is operated the shaft 11 is rotated and actuation of the crank 12 will result in a rocking and reciprocatory movement of the saw simulating element 33 and a saw simulation motion of each of the figures. 15

The wedge driving figure 24 consists of the fixed body and leg assembly 36 which has the pivotal arm sections 37 and 38. From the arm assembly extends the maul 39 which is adapted to strike the spike or wedge simulating element 20 40 on the shell 8.

As shown in Figure 5 numeral 41 generally refers to a trip mechanism which consists of the shaft 42 journaled through the bearing 43. Adjacent the shaft 42 is the bar 44 which has one 25 arm 45 connected to one end of the shaft 42 while the arm 46 at the other end of the bar 44 connects to the shaft 47. A spring 48 is wound on the shaft 42 and has one end bearing against the clevis 49 on the shaft 47. A pin 50 mounted adjacent the shaft 42 has a spring 52 thereon one end of which engages the arm 53 on the shaft 47. Extending from the shaft or pin 47 is the rod 54 which extends upwardly and connects to the arms 36—38. Numeral 55 represents 30 a finger extending from the shaft 42 into the path of the crank 13 so that each time the crank makes a revolution it strikes the finger 55 and causes tripping action of the mechanism 41, lifting and dropping the maul 39. 40

A tail structure suitably braced and ornamented extends from the body 6 and is generally referred to by numeral 57.

Manifestly, the shaft 42 cannot be rotated counterclockwise in view of the portion 46 of 45 the bar 44, but must be rotated clockwise in the direction of the arrow illustrated in Figure 4.

While the foregoing specification sets forth the invention in specific terms, it is to be understood that numerous changes in the shape, size and 50 materials may be resorted to without departing from the spirit and scope of the invention as claimed hereinafter.

Having described the invention, what is claimed as new is:

1. A display device of the character stated comprising a drive shaft having a crank therein, a movable figure, a trip mechanism, said trip mechanism including an arm adapted to be momentarily depressed by the crank while the shaft is being rotated, and a connection between the trip and the movable figure.
2. A display device of the character stated comprising a drive shaft having a crank therein, a movable figure, a trip mechanism, said trip mechanism including an arm adapted to be momentarily depressed by the crank while the shaft

is being rotated, and a connection between the trip and the movable figure, a hollow cylindrical structure simulating a tree trunk into which the shaft and its crank project, a wedge simulating element on the cylindrical structure, a mall simulating member swingably carried by the figure, said connection between the trip and the figure being connected operatively with the said swingable mall and adapted to swing the mall to strike the wedge simulating element. 5 10

CHARLES J. HENDERSON.
